US0D1112263S

(12) **United States Design Patent** (10) Patent No.: **US D1,112,263 S**
(45) Date of Patent: ** Feb. 10, 2026

(54) **DISPLAY SCREEN OR PORTION THEREOF
WITH GRAPHICAL USER INTERFACE**

(71) Applicant: **Apple Inc.**, Cupertino, CA (US)

(72) Inventors: **Taylor Gerard Carrigan**, San Francisco, CA (US); **Patrick Lee Coffman**, San Francisco, CA (US); **Thalia Jimena Echevarria Fiol**, Cupertino, CA (US); **Christopher P. Foss**, San Francisco, CA (US); **Bon Min**, Seoul (KR); **Eric Lance Wilson**, San Jose, CA (US)

(73) Assignee: **Apple Inc.**, Cupertino, CA (US)

(**) Term: **15 Years**

(21) Appl. No.: **29/902,574**

(22) Filed: **Sep. 14, 2023**

Related U.S. Application Data

(63) Continuation of application No. 29/734,894, filed on May 15, 2020, now Pat. No. Des. 1,002,641.

CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines depict a display screen or portion thereof, and form no part of the claimed design. The interior broken lines depict portions of the graphical user interface which form no part of the claimed design.
